UNITED STATES PATENT OFFICE.

MAX STOORMAN, OF NEW YORK, N. Y.

ROTARY TOOTH-BRUSH.

1,270,233.

Specification of Letters Patent. Patented June 18, 1918.

Application filed April 3, 1917, Serial No. 159,429. Renewed March 2, 1918. Serial No. 220,106.

To all whom it may concern:

Be it known that I, MAX STOORMAN, a citizen of Russia, and resident of the city of New York, borough of the Bronx, county of Bronx, and State of New York, have invented a new and Improved Rotary Tooth-Brush, of which the following is a full, clear, and exact description.

This invention relates to toilet articles and has particular reference to tooth brushes.

Among the objects of the invention is to provide a tooth brush of novel design or construction adapting it for superior cleansing qualities.

Another object of the invention is to provide a rotary tooth brush adapted to brush or cleanse by single operation or series of movements all of the exposed surfaces of the teeth, inside, outside and edges of the teeth of both jaws simultaneously.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of a preferred form of the invention.

Fig. 2 is a vertical sectional view of the same.

Fig. 3 is a vertical transverse section on the line 3—3 of Fig. 1; and

Fig. 4 is a side elevation of a modified form of the invention.

Referring now more particularly to the drawings I show a brush comprising two parts, namely the head 10 and the handle 11. The construction is preferably of a rigid nature and may be made of any material of a durable and sanitary nature suitable for the purpose of the device.

The head 10 comprises spaced parallel disks 12 and 13, the outer faces of which may be slightly convex or rounded, but have their inner or opposed faces substantially flat. Any suitable means may be provided to connect the two disks 12 and 13 and hold them in definite spaced parallel planes. I show for this purpose a short rigid stem 14 substantially cylindrical in form rigidly con-

nected to or made integral with one of the disks and having its other end tapped at 15 into the other disk. The axis of the stem coincides with the centers of the disks. 60

The inner flat faces 12' and 13' of the disks are provided with bristles 16 extending toward the central plane midway between the disks. I do not wish to be confined to any particular relative proportions 65 of these parts nor to any special amount of free space between the opposed sets of bristles, it being understood that in practice the inner disk 13 will be projected into the mouth cavity back of the teeth permitting 70 the teeth of both jaws to close toward each other toward the stem 14 and between the planes of the two disks. In this position then the bristles 16 of the two disks will bear upon the inner and outer surfaces of the 75 teeth of both jaws, at the same time the points of the teeth will be brought into position to be cleansed by the radial bristles 17 carried by the stem 14. The brush head may now be reciprocated along the teeth or rotated around the axis of the stem 14 causing the parallel bristles 16 to operate over the teeth with a circular motion, or these two motions, rotary and reciprocating, may be combined as may be desired. The surfaces 80 of all the teeth will thus be reached in a rapid and thorough manner, and the bristles especially those of the disks will cleanse all foreign matter from between the teeth more thoroughly than can be done with an 85 ordinary tooth brush.

The handle 11 being curved outwardly in the nature of a crank adapts the brush readily for rotation around the axis aforesaid as well as for reciprocating it. 95

The form of the improved brush shown in Fig. 4 is in all general aspects similar to that above described, the head 10' being the same while the handle 11' is offset from the head at 11^a to accommodate the operator's 100 lips or cheek between the disk 12 and the laterally projecting turn of the handle. This form of the device is better adapted for all rotary movement of the brush with respect to back teeth. The extreme end of 105 the handle 11^b, however, is bent more nearly into parallelism with the axis of the head than the other form whereby there is provided a better rotating or crank action.

I claim:

1. In a rotary tooth brush, the combination of a pair of spaced parallel coaxial

disks each having a convex outer surface, the disks having sets of bristles extending from each toward the other, a stem rigidly connected at one end to one of the disks and having a set of bristles extending laterally therefrom between the sets of bristles carried by the disks, the other end of the stem being connected to the other disk and serving to hold the disks in definite spaced relation to each other, and a curved handle rigidly connected to one of the disks and serving to rotate the same around the axis of the stem.

2. In a rotary tooth brush, the combination of a head and a curved crank shaped handle rigidly secured thereto and serving to reciprocate or rotate the head, said head comprising a pair of spaced coaxial members having convex outer surfaces with thin edges, means extending between the members and rigidly secured thereto, and sets of bristles secured upon the inner surfaces of the coaxial members and the exposed surface of the connecting means between them. 15
